UNITED STATES PATENT OFFICE.

JOSEPH L. WRIGHT, OF CLEVELAND, OHIO, ASSIGNOR, BY MESNE ASSIGNMENTS, TO
WESTERN ELECTRIC COMPANY, INCORPORATED, A CORPORATION OF NEW YORK.

TELEPHONE-EXCHANGE SYSTEM.

1,234,246.

Specification of Letters Patent. Patented July 24, 1917.

Application filed September 16, 1914. Serial No. 862,012.

To all whom it may concern:

Be it known that I, JOSEPH L. WRIGHT, a citizen of the United States, residing at Cleveland, in the county of Cuyahoga and State of Ohio, have invented certain new and useful Improvements in Telephone-Exchange Systems, of which the following is a specification.

My invention relates to telephone exchange systems, especially to types employing automatic switching mechanism for effecting connections between subscribers.

In systems of these types it is common practice to have automatic selection of trunks by what are termed selector switches.

The object of my invention is to provide means wherein the uniform use of the various trunks is obtained so that the wear on all of the apparatus will be the same.

A system for dividing the work among the various trunks is shown in Patent No. 831,876 to Keith, September 25, 1906. This patent shows the various selector switches arranged in groups and the corresponding bank contacts of the different groups connected to dis-similar trunks. In other words, one group of switches to select No. 1 trunk would only step to the first contact, while another group of switches to select the same trunk would have to step to No. 10 contact, and so on. This arrangement prevents uniform wiring and makes it necessary to have the various trunks connected to dis-similar contacts in the various groups of switches.

This method of wiring also allows idle trunks to be selected with a minimum number of steps of the switches. In other words, under ordinary conditions an idle trunk is selected within two or three steps of the switches and, consequently, the other contacts in the bank will be very seldom used and will accumulate dust and dirt which may interfere with proper connections when they are used.

With my invention uniform use of the trunks and of the various contacts is secured.

When all of the apparatus in a particular group is idle the last contact is the only one selectable. After the last contact in a row or group is selected then the contact immediately preceding it is rendered selectable, and after that particular contact is

selected the next preceding contact is rendered selectable, and so on. Supposing for instance that No. 7 contact is selected and while in use, contacts 8, 9 and 10 are released and rendered idle, then the next contact selectable will be No. 6. This method of selection is continued until the first contact is selected, whereupon No. 10 contact again becomes selectable if not in use.

For purpose of illustration I have shown my invention as applied to a full automatic system of the Strowger type, but, of course, the invention is applicable to any type of system employing switches for automatic selection of idle trunks.

My invention is illustrated in the accompanying drawings, wherein:

Figure 1 shows the manner in which uniform selection of trunks is secured.

Fig. 2 shows a subscriber's station, a first selector switch and a connector switch of the well known Strowger type.

Fig. 3 is a modification of Fig. 1.

Referring to Fig. 2, the first selector switch is provided with the usual rotary, vertical and test wipers 64, 61 and 84 respectively. These wipers are first moved in a vertical direction by predetermined impulses and then automatically in a rotary direction to select an idle trunk. The impulses at the subscriber's station are controlled by the operation of the push buttons 51 and 55.

I have not shown the details of the subscriber's station as it consists of the usual talking set and sending device mechanism.

For simplicity I have represented the sending device mechanism by the two push buttons 51 and 55. Button 51 transmits the vertical or directive impulses while button 55 transmits the rotary or test impulses.

The simultaneous operation of the two buttons causes the release of the automatic switches.

The selector switch and circuits are of the type shown in Patent No. 815,321 to Keith and Erickson, March 13, 1906, while the connector switch and circuits are of the type shown in Patent No. 815,176 to Keith and Erickson, March 13, 1906.

The circuits and arrangements in the foregoing patents show and describe in detail the operations of the various parts and it will be unnecessary for me to enter into a

detail description of the circuits I have used for illustration.

5 The vertical relay K controls the vertical magnet M which in turn causes the switch shaft carrying the wipers to step in a vertical direction. The rotary magnet M is controlled by the rotary relay L and causes the switch shaft to step in a rotary direction and automatically select an idle trunk.

10 While an idle trunk is being selected the test relay O remains in an energized condition in series with the back release relay P. This latter relay is of very low resistance and will not operate in series with 15 the winding of relay O. Relay O remains energized while an idle trunk is being selected, due to the fact that the busy contacts over which the test wiper 84 passes are grounded. As soon as an idle trunk is found, or when a non-busy contact is engaged, then the test relay O becomes deenergized and the switch wipers come to rest 20 on contacts leading to an idle trunk. While relay O is energized the circuit of the rotary magnet N is maintained closed in order 25 to keep the switch wipers rotating. As soon as relay O becomes deenergized the circuit of the rotary magnet N is broken and the side switches as usual in the Strowger 30 system assume their final position.

In assuming this position the rotary and vertical relays K and L are disconnected as well as the test relay O. When relay O is disconnected relay P has its winding connected directly to ground through the side switch arm 201, thereby rendering the selected test contact busy against other calls.

35 After the first selector switch engages an idle trunk or connector, impulses are transmitted by the subscriber's sending device 40 to cause the connector switch shaft carrying the wipers 73, 69 and 91 to first step in a vertical direction to the desired row and then step in a rotary direction to select the 45 contacts of the calling line.

Relays S and T are the vertical and rotary relays respectively, which respond to the impulses transmitted by the subscriber's sending device. The vertical magnet U in 50 operating causes the switch to step in a vertical direction, and after the rotary impulse is transmitted the side switch arms move to the second position, thus disconnecting the vertical magnet and in its place connecting the rotary magnet V. The next 55 series of impulses cause the rotary magnet to be operated, thereby allowing the switch to rotate and select the contacts of the called for line.

60 After the contacts of this line are selected the test impulse is transmitted, which causes the rotary relay T to be operated which in turn operates the private relay X and connects the release magnet Z directly to the 65 test wiper 91. If this test wiper is engaging

a busy or grounded contact the release magnet Z will operate and restore the connector switch. If, however, the called for line is not busy then the test impulse will simply cause the side switch arms to assume their 70 third or final positions. In taking the final positions the action of the side switch arms disconnects the rotary and release magnets but connects the ringing relay and also connects the rotary and vertical conductors leading 75 from the wipers of the first selector switch to the wipers of the connector switch.

The calling subscriber operating the push button 51 operates the ringing relay Y which was substituted for the rotary magnet 80 and causes ringing current from generator 110 to be applied to the called line.

In this particular instance I have not shown a substation of a called line, but simply the conductors 70 and 74 which extend 85 to the called line. The equipment of the called line is the same as that of the calling line.

In the system shown each line is provided with a first selector switch and it follows 90 that when connection is effected with the called line that the bridge cut-off relay such as R is operated.

The operation of this relay which is controlled over the test wiper 91 of the connector, serves to disconnect the rotary and vertical relays from the line wires to allow a clear circuit to the called sub-station.

At the termination of a conversation the calling subscriber in replacing his receiver 100 causes an impulse to be transmitted to both conductors at the same instant, thereby causing the restoration of the connector and the first selector switches in the usual manner.

From the foregoing description it will be seen that the selector switch in order to select an idle trunk rotates until the test wiper 84 finds a test contact which is not 105 grounded.

Referring now to Fig. 1, I have shown a set of test contacts number 1 to 10 inclusive which are multiplied and represent a certain group. Each set of multiple contacts, excepting No. 10 set, are normally connected 115 to ground through the back contacts of relays A, B, C, D, E, F, G, H and I respectively. No. 10 set of contacts is connected directly to the winding of relay J.

We will assume that a series of impulses 120 have been transmitted by the subscriber and that the wipers are in line with the proper row of bank contacts and that the test impulse has been transmitted. Under these conditions the test relay OX will remain 125 energized in series with the back release relay PX. These relays OX and PX correspond to relays P and X of Fig. 2. Relay OX will remain energized while the test wiper passes over the first 9 contacts which 130

are rendered unselectable by ground being connected respectively through the contacts of relays A to I inclusive. When No. 10 contact is reached the test relay OX will be 5 come deenergized and cause the side switch arm 201 to assume its final position and thereby connect ground directly to the winding of the back release relay PX. As soon as this connection is effected relays PX and 10 J are placed in series. The windings of these relays are such, however, that relay J will operate in series with the winding of relay PX, while the latter relay will not operate through the winding of relay J. 15 The operation of relay J disconnects ground from wire 35 leading to No. 9 set of contacts, but in its place connects the winding of relay I.

As soon as the foregoing change takes 20 place No. 9 set of contacts is rendered selectable and the next selector switch engaging this group of contacts will automatically step until No. 9 set of contacts are reached. As soon as these contacts are reached, relay 25 I is energized in the same manner as relay J. The operation of relay I removes ground from No. 8 set of test contacts and in its place connects the winding of relay H.

This method of selection is continued until 30 relay B is operated, whereupon No. 1 set of contacts are rendered selectable. The operation of relay A when No. 1 set of contacts are selected, simply serves to prevent ground being connected to its associated test contacts. The busy condition of a contact after selection is determined by ground 35 through the winding of a back release relay as PX.

From the foregoing description it will be 40 seen that the first selectable contact will be No. 10 and in order for that contact to be selected it is necessary for the wipers to pass over all of the preceding contacts and to insure the contacts being kept clean and 45 in constant use.

Of course, during certain periods a trunk will be used and then released before another selection is completed, and in that event if No. 10 contact was the one selected 50 and released it will also be the one next selected. However, as a rule with the arrangement shown in Fig. 1 the contacts and trunks will be uniformly used. If it is assumed that the last trunk used or selected 55 will be the last trunk released then the contacts will be selected in rotation.

In Fig. 3 I have shown a modified arrangement, whereby when a trunk is selected it will render the preceding trunk selectable regardless of whether the selected 60 trunk is released before the next selection occurs.

The arrangement shown is almost identical with that of Fig. 1, the only difference 65 being that each relay of the series A to J

inclusive when operated is maintained locked to ground through the back contacts of the preceding relay.

We will assume that the first contact selected is No. 10. The operation of relay J 70 associated with this contact will connect the winding of relay I to No. 9 set of contacts. If No. 10 trunk is released before the next selection, relay J will remain locked to ground through the back contacts of relay 75 I. This ground connection is made through a high resistance coil JJ. This resistance is sufficient to maintain relay J energized without rendering the test contact busy. Relay J remaining energized even though its 80 trunk is released allows No. 9 contact to be selected as ground is removed from that contact by the action of relay J. The next selector switch rotating to select an idle trunk in that group will select No. 9 contact 85 and thereby operate relay I. The operation of relay I removes ground from the locking contact of relay J, thereby allowing that relay to restore. The next selectable contact, however, will be No. 8 as relay 90 I will remain energized until No. 8 contact is selected, regardless of whether No. 9 trunk associated with No. 9 contact is released or not.

The contacts for shifting the windings of 95 the designating or control relays to their associated contacts (Fig. 3) are shown as the make before break type. The same type of contacts can be applied to the corresponding relays in Fig. 1 as such contacts are well 100 known and commonly used.

For simplicity I have shown but one set of complete circuits for the first selector and connector switches. Figs. 1 and 3 show groups of multiple contacts with their associated control relays. The contacts shown in Fig. 1 can represent the multiple contacts of a single group of selector switches 500, 600 and 700 while the contacts in Fig. 3 can represent those of different groups of 110 switches. Of course, each set of multiple contacts has an associated connector switch as shown in Fig. 2.

In the present instance I have only shown first selector and connector switches but 115 it will be understood that second selector switches can be interposed between the first selectors and connectors in the ordinary manner.

When second selector switches are used, 120 the bank contacts will be wired in the same manner as those of the first selectors. In other words each row of multiple contacts will be provided with its set of designating or control relays A to J inclusive. 125

In connection with Fig. 3, I have stated that the coil JJ is of high resistance so as not to render the test contact busy. Instead of simply using these series of coils AA to JJ for holding their respective relays ener- 130

gized, they can be of low resistance to render their associated test contacts busy against selection. In this case the energization of a designating relay renders its associated contact busy against selection until it is designated by the test wiper of the selector switch and until after the energization of the preceding designating relay of the series.

10 Having thus described my invention, what I desire to secure by Letters Patent is:

1. In a telephone exchange system, the combination with an automatic switch having test contacts, of means for designating a contact to be selected, means for causing said switch to select said contact, and electromagnetic means permanently associated with said contact adapted when the same is selected to render another of said contacts selectable.

2. In a telephone exchange system, the combination with an automatic switch having a group of associated test contacts, one of said contacts only being normally selectable, of means associated with said switch for selecting said contact, means whereby when the particular contact is selected the preceding contact passed over by the switch in making the selection is then rendered selectable, substantially as set forth.

3. In a telephone exchange system, the combination with an automatic switch having a row of associated test contacts, the last contact in said row being normally selectable, of means associated with said switch for selecting the last said contact, means whereby when the last contact is selected the preceding contact passed over by the switch in making the selection is then rendered selectable, substantially as set forth.

4. In a telephone exchange system, the combination with an automatic switch having a row of associated test contacts, of means associated with said switch for selecting one of said contacts, means whereby when the particular contact is selected the preceding contact passed over by the switch in making the selection is then rendered selectable, substantially as set forth.

5. In a telephone exchange system, the combination with an automatic switch having a row of associated test contacts, of means associated with said contacts whereby the first contact selectable by said switch is the last contact in the row, means whereby when the last contact is selected the preceding contact passed over by the switch in making the selection is then rendered selectable, substantially as set forth.

6. In a telephone exchange system, the combination with an automatic switch having associated contacts, of means permanently associated with said contacts whereby when particular contacts are selected the preceding contacts passed over by the switch

in making the selections are then rendered selectable, substantially as set forth.

7. In a telephone exchange system, the combination with an automatic switch having a row of associated contacts, certain of said contacts being unselectable in character while other of said contacts are selectable in character, means whereby when said switch engages a selectable contact one of said unselectable preceding contacts passed over by the switch in engaging the selectable contact is then rendered selectable in character.

8. In a telephone exchange system, the combination with an automatic switch having a row of test contacts, of means associated with said switch for selecting one of said contacts, means comprising a series of relays associated with and controlled over said contacts for designating the contact to be next selected, substantially as set forth.

9. In a telephone exchange system, the combination with an automatic switch having a row of associated contacts, of means associated with said switch for selecting said contacts, means permanently associated with and controlled over said contacts for designating the contact to be selected by said switch, and means for moving said switch into engagement with said contact, substantially as set forth.

10. In a telephone exchange system, the combination with an automatic switch having associated contacts, said contacts being engageable by said switch, means permanently associated with and controlled over said contacts for designating the contact to be engaged by said switch, and means for moving said switch into engagement with said contact, substantially as set forth.

11. In a telephone exchange system, the combination with an automatic switch having a row of associated contacts, means comprising a series of relays controlled over said contacts for determining the contact to be selected by said switch, substantially as set forth.

12. In a telephone exchange system, the combination with an automatic switch having a row of associated contacts, of a test brush associated with said switch adapted to wipe over said contacts, and means comprising a relay adapted when said test brush selects a particular contact to render a contact previously wiped over selectable.

13. In a telephone exchange system, the combination with an automatic switch having associated contacts, of means comprising a series of relays associated with said contacts for rendering the contacts selectable in rotation by said switch, substantially as set forth.

14. In a telephone exchange system, the combination with a plurality of automatic switches, each switch having associated multiple contacts, of means associated with and

controlled over said contacts for rendering the contacts selectable for service in rotation by said switches, substantially as set forth.

5 15. In a telephone exchange system, the combination with an automatic switch, trunk lines terminating therein, a test terminal for each trunk, and means associated with said contacts whereby the first contact selectable by said switch when all of the trunks are idle is the last contact in the row.

10 16. In a telephone exchange system, the combination with an automatic switch having a row of associated test contacts, means associated with said contacts whereby the first contact selectable by said switch is the last contact in the row, additional means whereby when the last contact is selected the preceding contact passed over by the switch in making the selection is then rendered selectable, substantially as set forth.

15 17. In a telephone exchange system, the combination with calling and called subscribers' lines, automatic switching mechanism comprising trunk selecting and line selecting switches for interconnecting said lines, contacts for said trunk selecting switches, means permanently associated with and controlled over said contacts for invariably causing said trunk selecting switches to select said line selecting switches in rotation.

20 18. In a telephone exchange system, the combination with calling and called subscribers' lines, selector and connector switches for inter-connecting said lines, of means for invariably causing selection for service of said connector switches in rotation by said selector switches for inter-connecting said lines, said means permanently associated with said connector switches and

directly controlled by said selector switches, substantially as set forth.

25 19. In a telephone exchange system, the combination with selector and connector switches, contacts for said connector switches at said selector switches, means permanently associated with and controlled over said contacts for invariably securing use of said connector switches in rotation by 50 said selector switches, substantially as set forth.

30 20. The combination with the stations of a telephone exchange, of a plurality of switches less in number than the number of 55 stations in the exchange, electrically operated means permanently associated one with each of said switches for causing the same to be selected invariably in a definite order, and means whereby an automatically selected one of said switches may be used in establishing a talking circuit between different stations.

35 21. The combination with a series of movable main switches, a series of auxiliary 65 switches, and electrically operated devices for moving a main switch to electrical connection with successive auxiliary switches, of means permanently associated with said switches for causing the same to be selected 70 invariably in a definite order, and means by which the circuit for the electrically operated devices will be automatically broken when the moved main switch reaches connection to a designated auxiliary switch. 75

In testimony whereof I affix my signature in presence of two witnesses.

JOSEPH L. WRIGHT.
